UNITED STATES PATENT OFFICE.

THOMAS J. ALLISTON, OF MARION, ILLINOIS.

MOWER-KNIFE SHARPENER.

1,248,241.

Specification of Letters Patent. Patented Nov. 27, 1917.

Application filed September 1, 1916. Serial No. 118,059.

To all whom it may concern:

Be it known that I, THOMAS J. ALLISTON, a citizen of the United States, residing at Marion, in the county of Williamson and State of Illinois, have invented certain new and useful Improvements in Mower-Knife Sharpeners; and I do hereby declare the following to be a full, clear, and exact description of the invention, such as will enable others skilled in the art to which it appertains to make and use the same.

This invention relates to improvements in that type of mower knife sharpener in which the sharpening device is pivotally mounted within the knife guard, and adapted to be swung on the pivot by the teeth of the cutting blade during the passage of the blade through the guard and to engage the teeth so as to effect sharpening of the same, and an object of the invention is to mount the sharpening device within the guard in such a novel manner that the same can have both vertical bodily movement and vertical swinging movement, so that the entire cutting edge of the blade will be engaged by the sharpening device as the blade passes through the guard.

Another object of the invention is the provision of a novel type of knife guard having a receiving recess therein underlying the sharpening device for collecting dirt and such matter that will be liberated from the teeth of the knife during the sharpening operation, the walls of the recess having discharge openings therein to admit of the escape of the collected matter from the recess so that the collected matter will not interfere with the sharpening operation.

Other objects will appear and be better understood from that embodiment of my invention of which the following is a specification, reference being had to the accompanying drawings forming a part thereof, in which:

Figure 1 is a top plan view of the guard with the improved sharpening device associated therewith,

Fig. 2 is a side view thereof,

Fig. 3 is a longitudinal section taken through the guard, showing the position assumed by the sharpening device during the sharpening operation,

Fig. 4 is a section taken on the line 4—4 of Fig. 2, and

Fig. 5 is a detail perspective view of the sharpening device detached from the guard.

Referring to the drawings in detail, the numeral 1 designates the guard having its rear end provided with an attaching flange 2, adapted to be secured to the portion 3 of a mowing machine by means of a bolt 4 and a nut 5. The forward end of the guard tapers, as shown at 6, and formed on the upper side of the guard, adjacent the tapered end, is a pair of spaced apertured ears 7. A U-shaped frame 8 is disposed above the upper side of the guard 1 and has the ends of the sides thereof formed integral with the ears 7. A plate 10 is secured to the upper side of the guard 1 and underlies the U-shaped frame 8, and has its opposite longitudinal edges beveled, as shown at 11, to provide the cutting edges which coöperate with the cutting edges of the teeth 12 carried by a cutter blade 13, which latter reciprocates through the space between the frame 8 and the plate 10.

The sharpening device is located within the U-shaped frame 8 and is movable therein and consists of a sharpening element 14, formed preferably of emery and having a very fine operating surface, the said sharpening element being carried by a frame 15, the rear end of which is provided with an extension 16, which is received between the ears 7 on the guard and the sides of the frame 8, and is provided with a diagonally extending elongated slot 17 that receives a pivot pin 18, which extends through the opposed ears 7, as shown more particularly in Fig. 3 of the drawings. The operating surface of the sharpening element 14 is rounded, as shown at 19, and extends throughout the length of the element 14. The plate 10 is provided with a central recess 20, the walls of which are beveled, as shown in Fig. 4, and the said recess 20 is adapted to receive the lower grinding or sharpening surface of the sharpening element 14 after the sharpened tooth has passed from the guard, and before the next adjacent tooth is moved into the guard. This admits of the sharpening element 14 assuming a position where it will effectively engage the tooth of the cutter when inserted within the guard. An inverted substantially U-shaped spring 21 has one end secured to the upper side of the tapered end of the guard 1, and its opposite end slidably received by a guide slot 22 formed on the upper side of the frame 15, which carries the grinding or sharpening element 14. When one of the cutting edges of a tooth is

moved into the guard the rear end thereof will be the first portion to be presented beneath the sharpening element, owing to the triangular shape of the tooth, and will effect 5 vertical pivotal movement of the cutting element carrying frame 15. During the travel of the tooth through the guard and the gradual presentation of the outer end of the cutting edge beneath the sharpening element, the sharpening element-carrying frame 15 will be given vertical bodily movement, the slot 17 which receives the pivot 18 admitting of this vertical bodily movement of the frame 15 being effected. By virtue of 10 the fact that the sharpening element-carrying frame has bodily movement during the passage of the cutting edge of the tooth therebeneath, and also by reason of the fact that the free end of the spring rests on the 15 upper side of the frame 15, the pressure of the sharpening element 14 against the cutting edge of the tooth will be constant. The guard 1 is provided, at a point below the recess 20 in the plate 10, with a chamber 23 20 which is adapted to receive the material scraped or liberated from the cutting tooth during the sharpening operation. The side walls of the chamber 23 are provided with opposed elongated slots or openings 24, which will admit of the matter collected in 25 the chamber 23 being discharged therefrom, so that danger of the collected matter filling the chamber 23 and preventing the cutting element 14 being lowered to the position 30 whereby the sharpening surface will be prevented from being received by the recess 20 in the plate 10, will be overcome.

Having thus described my invention what I claim as new, is:

1. In a mower knife sharpener, the com-

bination with a knife guard, apertured ears fixed on the upper side of the guard, a frame overlying the guard, a sharpening element carried by the frame, an extension carried by the frame and located between the ears 45 on the guard and having an elongated slot therein, and a pivot pin extending through the ears and the slot in the extension.

2. In a mower knife sharpener, the combination with a knife guard, of a sharpening element-carrying frame, and means for connecting the frame to the guard for tilting and vertical bodily movement on the guard, and a spring having one end connected to the guard and its opposite end 50 free and overlying and resting on the upper side of the sharpening element carrying frame.

3. In a mower knife sharpener, the combination with a knife guard, of a spring 60 having one end secured to the guard, a sharpening element carrying frame having a slot therein for receiving the other end of the spring, and means for connecting the sharpening element carrying frame to the guard for tilting and vertical bodily movement on the guard.

4. In combination, a mower knife guard, a knife sharpening element mounted on the guard, the said guard having a collecting chamber therein underlying the knife-sharpening element, and two of the opposed side walls of the chamber having discharge openings therein, for the purpose specified. 70

In testimony whereof I affix my signature in presence of two witnesses.

THOMAS J. ALLISTON.
